[57] CLAIM

The ornamental design for a telescoping mirror, as shown and described.

DESCRIPTION

FIG. 1 is a perspective review of a telescoping mirror showing the new design;

FIG. 2 is a right side elevational view thereof;

FIG. 3 is a front elevational view thereof;

FIG. 4 is a left side elevational view thereof;

FIG. 5 is a back elevational view thereof;

FIG. 6 is a top plan view thereof;

FIG. 7 is a bottom plan view thereof;

FIG. 8 is a perspective view thereof with the handle in unattached condition;

FIG. 9 is a perspective view thereof with the handle in extended condition; and,

FIG. 10 is a perspective view of a second embodiment of the telescoping mirror, the sole difference from the first embodiment being in the different configuration of the mirror.
